UNITED STATES PATENT OFFICE.

CHARLES L. GOODRUM, OF URBANA, OHIO, ASSIGNOR, BY MESNE ASSIGNMENTS, TO
WESTERN ELECTRIC COMPANY, OF NEW YORK, N. Y., A CORPORATION OF ILLINOIS.

SWITCHES AND CIRCUITS FOR AUTOMATIC TELEPHONE-EXCHANGES.

1,147,390.

Specification of Letters Patent. Patented July 20, 1915.

Application filed May 5, 1909. Serial No. 494,098.

To all whom it may concern:

Be it known that I, CHARLES L. GOODRUM, a citizen of the United States, residing at Urbana, in the county of Champaign and 5 State of Ohio, have invented certain new and useful Improvements in Switches and Circuits for Automatic Telephone-Exchanges, of which the following is a specification.

10 My present invention relates to automatic telephony in which the connections between subscribers' telephone instrument circuits are effected by electromechanic switching devices located at the central office or exchange and it has for its primary object to 15 simplify this mechanism and increase its efficiency.

To this end my invention comprehends employing in the first instance a switching 20 mechanism operating upon the central energy principle of telephony in which the wipers are adapted to move both in a vertical and a rotary direction to select particular contacts in the bank of terminals 25 with which they coöperate and to employ said switch as a finder to select the line contacts or terminals of a particular incoming line from those of a plurality of such lines, said switch being entirely automatic 30 in its operation and requiring no act on the part of a calling subscriber to actuate it after the subscriber has removed his receiver from the hook. My invention includes the providing of operating and controlling devices 35 for the finder switch which are common to all the incoming lines leading thereto, whereby it may be automatically started, arrested and released by current impulses despatched by any one of a number of subscribers.

In connection with the finder switching mechanism I have also provided means whereby the incoming lines may be divided into groups and each group served by one 45 of several such switches in case another or others are in use.

My invention has for its further object to provide for use in conjunction with the finder switch a connector switch by means 50 of which the line selected by the former may be automatically connected to any one of a plurality of outgoing telephone instrument

circuits and to apply to each connector a novel arrangement of the operating and controlling mechanism whereby its functions 55 may be all performed by impulses of current transmitted over a full metallic circuit.

As a further object my invention provides a novel arrangement of parts for supplying current for talking purposes to the called 60 line and for automatically releasing the connector switch in the event the line selected by it is otherwise in use to restore said switch to its normal position and supply the calling line, seeking the connection, with 65 the busy signal.

To these and other ends the invention consists in certain improvements and combinations of parts all as will be hereinafter more fully described, the novel features being pointed out in the claims at the end of the specification.

In the drawings: Figure 1 is a diagrammatic view illustrating generically the line connections as they may be effected between 75 two instrument circuits by means of the finder and connector switches, the operating mechanism thereof being omitted. Fig. 2 is a diagrammatic view showing a plurality of telephone instrument circuits arranged 80 in groups and a finder switch for serving them. Fig. 3 is a diagrammatic view of the operating mechanism of a finder switch and an incoming or calling instrument circuit. Fig. 4 is a similar view of a connector 85 switch and an outgoing or called instrument circuit. Fig. 5 is a diagrammatic view showing a plurality of finder switches associated with a plurality of groups of incoming instrument circuits. Fig. 6 is a similar 90 view illustrating the method of associating said switches with the different groups of instrument circuits for independent operation in response to calls originating on any line of a group and also showing the manner of connecting the finder switches to facilitate the distribution of traffic when two or more subscribers in any group desire to establish successive connections. Fig. 7 is a diagrammatic perspective view of a 100 switching mechanism illustrating the various banks of contacts and the wipers co-operating therewith, together with the side switch mechanism.

Similar reference numerals in the several figures indicate similar parts.

In a telephone exchange system embodying this invention the connections between 5 different telephone lines are automatically set up, or effected, by apparatus arranged at the central office or exchange, and the telephone lines or circuits leading thereto are divided into two classes comprising, 10 first, incoming lines, or those on which calls are originated by subscribers who desire to establish communication with other parties and, secondly, outgoing lines over which the calls are despatched to signal said called 15 parties. Each line may, at different times, be of either class and it will, therefore, be understood when these lines are referred to in the following description, that an incoming line, or calling circuit is one leading 20 from a subscriber's telephone or station over which impulses of current are sent to connect said line to an outgoing line and that the latter is the called circuit on which the signaling devices are actuated, when the 25 connection has been set up or completed between the telephone instruments of the calling and the called subscribers.

In the system embodying the present invention it is possible to connect by means of 30 the central office, or exchange, apparatus a given line with any other line and to this end all the lines lead to terminals on a finder switch, or a plurality of such switches, and to similar terminals on an associate connector switch or switches. The finder switch 35 performs the function of selecting an incoming line on which a call has been originated, and the connector switch, associated therewith, performs a similar function in selecting the outgoing line leading to a particular telephone instrument, or subscriber's station, with which the called subscriber desires to communicate. The movable elements or wipers of the finder switch and its 40 associate connector switch are tied together when the respective switch mechanisms have performed their functions and have operated the shafts carrying the wipers to position the latter in engagement with the selected line terminals so that the talking circuit from the incoming to the outgoing line 45 is extended through the wipers and may be retained until one of the two communicating subscribers desires to effect a disconnection of said lines.

The mechanical details of these switches are not shown in this application, as they may be of the well known Strowger type of 50 apparatus in which the switch wipers are mounted upon a longitudinally movable and revolute shaft arranged at the center of an arcuate bank containing contacts arranged in horizontal rows and in vertical tiers. The operating mechanism of the 55 switch comprises mechanism for adjusting

the shaft longitudinally to position the brushes thereon in alignment with one or another of the rows or contact levels, as they are called, and also means for rotating the shaft to position the wipers in engagement with any particular set of contacts in the row or level selected. 70

In Fig. 1 a single finder and connector switch of this character has been shown diagrammatically to illustrate the manner of connecting two or more telephone instrument circuits indicated generally by A, B, D and E, the finder switch F and the connector switch C being shown with the respective contact elements or wipers in operated position establishing a connection between instruments A and B and in dotted lines these parts are shown in a position which they would occupy to connect instrument E with instrument D. In both of these connections 80 A and E are the incoming or calling instrument circuits, while B and D respectively are the outgoing or called instrument circuits. 85

The telephone instruments may be of the usual or any preferred construction comprising generally a transmitter 1, a receiver 2, and the signaling devices or bells 3, all of which are arranged in the circuit of the line wires A'-A² of instrument A, and B'-B² 90 of instrument B. The instrument circuits are normally open at each subscriber's station at the contacts A³-B³ which are controlled by the receiver hook and are closed when the latter is released by the subscriber removing his receiver therefrom. Each pair of wires constituting the circuits of the telephone instruments is extended to the aforementioned switches located at the central office and terminate in immutable contacts located thereon, those of the wires A'-A² being located on the switch F, as indicated by A¹⁰-A²⁰, the corresponding contacts on the switch C being indicated by A¹¹-A²¹, said contacts being tied together 100 by conductors A¹²-A¹³, the similar contacts of the wires B'-B² on the switch F are indicated by B¹⁰-B²⁰ and on the switch C by B¹¹-B²¹, said pairs of contacts being also tied together by wires B¹²-B¹³. The operating mechanisms controlling the movable elements or wipers of the two switches have been omitted from these illustrations, as well as the side switches employed for cutting the operating mechanism into and out 110 of the operating circuits and cutting the lines through from one switch to another, but as will appear more fully hereinafter, this mechanism is designed to cause such switches to move progressively both vertically and horizontally while their respective brushes engage contacts or terminals representing a large number of telephone lines. The wipers of the switch F are indicated by F'-F² and those of the switch C 115 120 125 130

by C'-C², the corresponding wipers of the two switches being connected by wires 4 and 5.

From an inspection of Fig. 1 it will be seen that the complete circuit between the instruments A and B may be traced as follows: Instrument A, wire A', contact A¹⁰, wiper F', wire 4, wiper C', contact B¹¹, wire B', instrument B, wire B², contact B¹¹, wiper C², wire 5, wiper F², contact A²⁰, wire A², instrument A. The foregoing is predicated upon the fact that the call originated at the instrument A and the mechanism of the finder switch operated to pick up the contacts of the incoming circuit A'-A², after which the switch C was actuated to connect said circuit with the terminals of the outgoing line B'-B².

Supposing a reverse operation to be effected in a like manner. The movable elements of the finder switch F traverse its bank of contacts, or terminals, until reaching the terminals B¹⁰-B²⁰ of the line B'-B² then the connector switch C operates to pick up the terminals A¹¹-A²¹ of the line A'-A². The circuit between the two telephone instruments will then be traced as follows: Instrument B, wires B², B¹³, contact B²⁰, wiper F², wire 5, wiper C², contact A²¹, wires A¹³, A², instrument A, wires A', A¹², contact A¹¹, wiper C', wire 4, wiper F' contact B¹⁰, wires B¹²-B', instrument B.

The instrument circuits D and E, indicated in Fig. 1, comprise the component parts described in the corresponding circuits A and B and these circuits are shown to illustrate the longitudinal movement of the switch shafts which may be adjusted vertically to position the wipers thereon in alinement with the contacts or terminals of a particular row or level when they may be rotated to effect the connection illustrated by the dotted lines, the brushes F' and F² of the finder switch connecting the terminals of the incoming line E and the corresponding brushes C' and C² of the connector switch engaging the terminals of the outgoing line D.

The switches.—The general arrangement of the essential elements of the switching mechanism is best shown in skeleton form in Fig. 7, in which the vertical rotary shaft, indicated by 10, is provided with a plurality of wipers 11, 12, and 13, of which a greater or less number may be employed as occasion requires. At the upper end of the shaft is a drum 15 provided with longitudinally extending ratchet teeth with which coöperates a pawl 16 on an arm 17 adapted to be attracted whenever the rotary magnet 18 is energized. The shaft is held in its adjusted rotary position by means of the detent 19. Surmounting the drum is a ratchet member 20 having annular teeth with which coöperates a pawl 21 on an armature lever 22

adapted to be attracted by the vertical magnet 23 whenever the latter is energized for the purpose of raising the shaft 10 one or more steps in a vertical direction in which position it is held by a detent 24. The shaft 70 is normally rotated in one direction to carry the several brushes or wipers thereon beyond the ends of the rows of contacts by means of the spring 25 having one end attached to the shaft and the other to an arm 75 which projects laterally from the shaft and bears against a post rigidly mounted on the supporting frame of the switch mechanism which has been omitted from this illustration.

Movable vertically with the shaft of the finder switch but not partaking of its rotary movement is a wiper 28 which may be conveniently mounted on the arm 26 to engage with the decimal contact strip or comb 29 85 which latter is provided with a plurality of contacts which are insulated one from another and of a number corresponding to the vertical distance through which the shaft 90 may be adjusted.

The several wipers 11, 12, and 13 coöperate with separate rows of contacts and are adapted to simultaneously engage in the different rows, terminals dedicated to particular instrument circuits. For instance, 95 the brushes 11 and 12, corresponding to the brushes F' and F² of the finder switch F are adapted to engage with the terminals 11^a and 12^a of the line wires of incoming circuits and the brush 13 coöperates with 100 contact 13^a which are apportioned to said circuits for purposes to be presently described. All of the aforementioned contacts are shown in Fig. 7, as arranged upon the first level so that they will be simultaneously engaged by the respective brushes upon the first upward movement of the shaft 10 and the first rotary movement which may be imparted thereto, but it will be understood that each row of each level 105 contains a plurality of similar contacts for different telephone circuits so that a large number of the latter, preferably 100 in all, may be accommodated upon a single switch.

In switches of this character, the mechanism for operating them comprising the vertical, rotary and release magnets, are controlled by means of a side switch indicated by S in Fig. 7, comprising the wipers 30, 31, 32, 33 and 34, each of which engages a separate 120 row of three corresponding contacts over which they are stepped by means of an escapement mechanism & controlled by a private magnet P which operates in conjunction with the vertical and rotary magnets 23 125 and 18 in the well known manner. The release magnet indicated by 35, performs a dual function of disengaging the detents 19 and 24, to permit the switch shaft 10 to be rotated into its normal position by the spring 130

25 and to descend to its normal position, and also to restore the side switch S to its normal position.

The finder and connector switches are actuated by electromagnetic devices peculiar to each, those of the finder switch being automatically set into operation, and controlled by secondary circuits, which are established when an instrument circuit is closed at the subscriber's station, and the mechanism of the connector switch is rendered operative when the finder switch has picked up the incoming or calling circuit and is controlled by impulses of current which may be despatched by a suitable form of impulse transmitter located at the subscriber's station, to select a given outgoing line, or called circuit. Accordingly the instrument circuit, comprising wires A'—A², is extended, as indicated at A¹⁴, A²⁴, Figs. 1, 2 and 3 to normally closed contacts A⁴¹—A⁴², one of which is mounted upon a spring finger provided with a projection 46 adapted to coöperate with contacts on an impulse transmitter A⁴ to thereby transmit or send over the operating circuit one or more impulses of current when the circuit is closed at the hook contacts A³.

When the line has been extended through the finder and connector switches the calling subscriber causes the bells or signaling devices of the called instrument circuit to be operated and to this end each instrument circuit is provided with a push button A⁷ (Fig. 3) operating a contact spring a⁷ connected to earth as shown and adapted to engage the line contact spring a⁸. The latter engages a contact a⁹ and is retracted out of engagement therewith at a¹⁰ to open the calling instrument circuit after one side thereof has been grounded, these parts being arranged in this manner to establish and maintain a ground on one side of the calling instrument circuit to prevent the release of the switches during the ringing period which would otherwise occur when the instrument circuit is destroyed, all as will appear more fully hereinafter.

The electromagnetic mechanism for causing the various switches to perform their respective functions, are all adapted to be operated from a common battery, but in order to facilitate the description and illustration, and render a more comprehensive understanding of the various circuits to be had, these are shown in the various diagrammatic views as receiving current from different sources or sets of batteries Z'—Z², etc. To render the circuits easy to trace they are shown with the conventional ground connections but it will be understood that when the term ground is employed and shown, it refers to a connection leading directly to one side of the main battery, so that a telephone system embodying this in-

vention, when installed in working order, is entirely free of the so-called grounds employed for actuating the switching parts of the apparatus, thereby eliminating line disturbances or other troubles attributable to this cause.

The finder switch.—To enable a comprehensive understanding to be had of the various features of the invention, it will be advantageous and facilitate an understanding of the system to first take up the various steps performed in connecting two instrument circuits over a single group of switches, it being understood at the outset that this operation is precisely the same on each group. In order to illustrate this feature of the invention I have shown in Fig. 2 the manner of grouping incoming telephone lines and their connections with a single finder switch. In Fig. 5 three of such switches have been shown to illustrate particularly the multiplying of the instrument circuits on the various finder switches and also the multiplying of the groups in which these lines are divided, on said switches. Fig. 6 shows the method of wiring or connecting as many as ten different finder switches to facilitate the distribution of the traffic load, each switch being directly under the control of each incoming instrument circuit in its particular group.

The finder switches are further interconnected so that when a switch is actuated by a particular instrument circuit in its group, another is automatically connected to said group in readiness to respond to a second call originating in the same group of instrument circuits. Similarly the second switch joins a third to the same group and so on with the result that all the instrument circuits of a particular group may establish connections over an equal number of finder switches, each of which is primarily intended to only serve the instrument circuits in the group to which it is assigned.

As many separate instrument circuits may be brought together in a single group, as good practice or business conditions may determine. This grouping of the lines being usually arranged upon a ten per cent. basis, whereby ten subscribers out of every 100 may effect connections over their respective finder and connector switches at the same time.

The instrument circuits.—In Fig. 2 circuits for four subscribers' lines have been shown, the first three of which are arranged in one group, while the last illustrates a second group. With each subscriber's line is associated the individual line actuated relays A⁵, B⁵, J⁵ and H⁵ respectively, which are arranged at the central office and are adapted to be energized when their respective instrument circuits are closed to energize the circuit of a group actuated or mas-

ter relay, such as G or G' each of which is common to all instrument circuits in its particular group there being as many master relays as there are groups. Each of these 5 relays is adapted to close the starting circuit which energizes its respective finder switch. Also associated with each line is a cut-off relay, those corresponding to the lines mentioned being indicated by A⁶, B⁶, J⁶, and H⁶, 10 the function of which is to restore their corresponding actuated relays A⁵, etc., to normal position when a finder switch has picked up the terminals of its corresponding instrument circuit. In Fig. 2 the single finder 15 switch illustrated therein, which is typical of all of these switches, is shown provided with contacts for the line wires, the cut-off relay and the test wire of all of the instrument circuits, all of which are for convenience, in illustration, shown in this figure as arranged upon the first levels of the respective banks of terminals. It will be noticed in Fig. 2 that the four and in Fig. 7 20 the three last mentioned terminals of each line appearing in the different banks and constituting a set are arranged in vertical alinement so that the respective contacts dedicated to any particular line are simultaneously engaged by all of the brushes or 25 wipers as they are progressively advanced by the rotary movement of the switch shaft. The terminals constituting the set for each line are located in the same level in each bank, that is, if the line terminals appear 30 in the second levels or horizontal rows, then the coördinate terminals of the cut-off and test circuits will be found in the second levels of their respective banks, etc.

Multiple terminals of each line with the 35 multiples of its cut-off and test circuits appear in the same position in front of each finder switch as shown in Fig. 5, but as this method of trunking is well known, further description thereof is deemed unnecessary.

Referring now particularly to Fig. 2, it 40 will be seen that the line terminals of instrument circuit A are located one beneath the other and that beneath these appear the cut-off terminal f¹⁵ and the test wire terminal f¹⁶, with which coöperate the brushes f¹⁷ and f¹⁸ respectively. Leading from the terminal f¹⁵ is a wire A¹⁶ leading to the cut-off relay A⁶, the other terminal thereof being supplied at times with current from the 45 battery Z². The line finding test wire A¹⁵ leads from the contact f¹⁶ to a back contact a¹⁵, with which the armature a⁵ of the individual line actuated relay A⁵ normally engages, said armature being connected by 50 a wire z⁴ to the ground side of the battery Z², which is connected to the group actuated master relay G arranged in a circuit including the wire g terminating in a forward contact g' engaged by the armature a⁵ when 55 the latter is attracted. One end of the coil of the line actuated relay A⁵ is connected to the battery Z³, the other extremity of which is connected by the wire a' to the back contact a² with which normally engages the armature a⁶ of the associated cut-off relay, 60 said armature being connected with one side of the instrument circuit by the wire a³ joined to the line wire A². A second armature controlled by the cut-off relay, indicated by a⁴, is connected by the wire a¹² 65 joined to the other line wire A'. This armature normally engages a back contact a¹² which has a grounded connection z³. (See Fig. 3).

In order to remove the control of the line 70 from the subscriber after a call has been started during the operation of the finder switch and until the latter has picked up the terminals of said incoming line I arrange therein a normally open bridge which is 75 closed by the closing of the subscriber's instrument circuit to shunt out the telephone instrument. In Fig. 3 this bridge is shown, comprising the wires a²⁰ and a²¹ leading from the wires A' and A² respectively one 80 being connected to a forward contact a²² and the other to an armature a²³ coöperating therewith and arranged on the line actuated relay A⁵. The latter being energized by the closing of the instrument circuit at the hook 85 contacts A³ attracts and holds the armature a²³ in engagement with the contact a²² until the relay A⁵ is cut off by the operation of the relay A⁶ controlled by the finder switch. Primarily this shunt prevents the opening 90 of the circuit of the group actuated or master relay should the calling subscriber inadvertently abandon the call while the finder switch was moving either vertically or in a 95 rotary direction. This arrangement of the 100 circuit, it will be seen causes a switch, when it has been started to actually complete its search for the terminals of the calling line.

The corresponding parts to those just described in connection with instrument circuit A are found illustrated in connection 105 with the remaining instrument circuits, said parts being indicated by the use of letters B, J and H, and b, j and h, with the appropriate exponents, reference to which will be 110 made hereinafter in explaining the operation of certain parts of the apparatus. Attention is called to the fact that the master relay, such as G of each group, is arranged 115 in a compound circuit which is adapted to be 120 closed by the attraction of any of the armatures a⁵, b⁵ or j⁵ of the individual line actuated relays of the lines constituting the group and from this arrangement of the 125 parts it will be seen that by closing any instrument circuit by the removal of the receiver from its hook the master relay of the group in which said line is included, will be 130 actuated.

The decimal test strip or commutator in-

dicated by 29 in Fig. 7, contains contacts insulated from each other, one for each group of lines which are normally connected with the ground side of the battery circuit to control the vertical movement of the switch shafts, said circuits being adapted to be opened by the operation of their respective master relays to arrest the upward movement of said shafts to position the wipers thereon in alinement with the horizontal rows or levels in which appear the different terminals of a line of any group on which a call has been originated. The lowermost contact of the strip, indicated by 5 f, is a home or starting point and is normally grounded, as indicated at z⁵ (Figs. 2 and 3). From the first contact on the decimal strip 29 leads the wire g² terminating in the back contact g³ which normally engages the armature g⁴ of the master relay G of the first group, said armature having a grounded connection z¹⁵. Likewise leading from contact No. 2 is the wire g²⁰, terminating in the back contact g³⁰ of the armature g⁴⁰ of the master relay G of the second group, said armature being grounded as indicated at z⁵¹ (Fig. 2). From the remaining contacts of the strip extend similar wires, as indicated by g²¹ and g³¹ which lead to similar contacts of the armatures of the master relays of additional groups of lines, not shown, said wires g²¹, g³¹, etc., being each grounded when all the instrument circuits in their respective groups are idle.

35 In Fig. 3 a single telephone instrument circuit has been illustrated showing its line and cut-off relays, the group actuated or master relay and the finder switch with its operating mechanism and in order to facilitate the description the sets of terminals of this line are shown in the switch banks as being arranged in the third level and the third group.

45 In the operation of a switch of this character, the first actuation effected is the vertical movement of the switch shaft F¹⁰ the required number of steps, by the successive impulses of current supplied to the vertical magnet F²³. Then the rotary movement of 50 the shaft is caused by successively energizing the rotary magnet F¹⁸. When the switch mechanism is in its normal position, the vertical magnet is in the normal open starting circuit extending through the side switch arm f³² which together with other arms of the side switch, is allowed to escape and take one step, when the impulses transmitted to the vertical magnet have ceased. This disconnects the latter and connects in the rotary magnet and upon the cessation of impulses through the latter, said switch takes its second step and escapes into the third position to disconnect the rotary magnet and set the arms f³⁰, f³¹ in position 55 to extend the calling instrument circuit over

the wires 4^A and 5^A leading to the connector switch, at which time the arms f³⁰ and f³¹ respectively engage the contacts f³⁵ and f³⁶ of the wires f³⁷ and f³⁸ leading from the switch wipers F' and F².

70 The side switch arm f³² is normally connected to ground, as indicated at z⁷ and in its normal position, shown in Fig. 3, rests in engagement with a contact forming the terminal of the wire f³⁹, which is connected to one end of the coil of the vertical magnet F²³. In its second position the arm f³² engages the contact f⁴⁰ which is the terminal of the wire f⁴¹ connected to one end of the coil of the rotary magnet F¹⁸ and in its third position said arm contacts with the terminal f⁴² joined by the wire f⁴³ to the wiper f¹⁷ which latter cooperates with the terminals of the cut-off relay circuits grouped on this switch. The arm f³³ engages the contact f⁴⁴ 80 and normally closes the holding circuit of the vertical magnet which includes the wire f⁴⁵ leading from the brush f²⁸ over which the holding circuit is energized during the vertical movement of the switch shaft during the time said brush receives current by reason of its successive engagement with the contact plates of the commutator or decimal test strip f²⁹ so long as the branch circuits leading from these contacts are closed, as 90 will more fully appear hereinafter.

95 Associated with the rotary and vertical magnets is the private magnet P, which as before explained, controls the escapement mechanism of the side switch. This magnet 100 is adapted to be energized by the impulse of current transmitted to it over the booster line or starting wire which is energized whenever the master relay of the group of instrument circuits to which the finder switch is dedicated is energized, providing this particular finder switch is in its normal position otherwise some other finder switch will be actuated by this impulse of current. The booster circuit comprises the wire p' terminating in the forward contact g⁶ of the armature g⁴ of the group actuated master relay G and extending to the side switch arm f³⁴ which latter when in its normal position connects it to the private magnet P.

110 Each master relay controls one of these booster lines or starting circuits which leads directly to the side switch arm of its particular finder switch. In Fig. 2 this circuit of the second group is indicated by p² and in Fig. 5, it is shown connected to the side switch arm f³⁴² and in this figure said circuit of the third group indicated by p³ is shown connected to the side switch arm f³⁴³ of the third finder switch. Fig. 6 shows this method of associating the finder switches with their respective groups of lines, more extensively, the side switch arms of ten different switches being shown and 120 125 130

indicated by f^{34} (of the first group) f^{342}, f^{343} etc., to f^{350} (of the tenth group) each of which is connected with its respective booster line or starting wire p^1, p^2, p^3 etc. 5 A greater or less number of finder switches may be employed as occasion requires, and in order to render other finder switches available, in the event two or more subscribers in any particular group desire to 10 make successive calls, I interconnect the switches in such a manner that when any of them have been operated they will automatically connect in another, or others, which will respond to another call from a 15 subscriber whose particular group switch has been previously operated. To accomplish this object I provide contacts which are engaged by the side switch arms f^{34}, f^{342} , etc., whenever the latter are moved into the 20 third position, which are joined or tapped onto the starting wires of the adjacent finder switch. In Figs. 5 and 6 these contacts are designated by p^{11}, p^{12} , etc., to p^{20} . The contact p^{11} of the first switch is connected to the starting wire of the last switch in the series by a wire p^{21} , that of the second switch is connected to the starting wire of the first switch by a wire p^{22} and the remainder are likewise connected, each with 25 the adjacent switch as shown in Fig. 6. The booster lines or starting wires are normally connected with the private magnets of their respective finder switch operating mechanisms by the side switch arms f^{34}, f^{342} , etc., when the latter engage the contacts h^1, h^2, h^3 , etc. by the wires h^{11}, h^{12}, h^{13} , etc. (Fig. 6). However, in order to disconnect 30 said magnets from the boosters or starting wires, after the latter have set the switches in motion, each of the wires, h^{11}, h^{12}, h^{13} , etc. have a set of contacts interposed in them which are closed when the switch shafts are in normal position. These are 35 called the off-normal contacts and comprise springs h^{21}, h^{22}, h^{23} , etc. joined to the terminals, h^1, h^2, h^3 and adapted to close against the back contacts h^{31}, h^{32}, h^{33} , etc., of the wires h^{11}, h^{12}, h^{13} , etc. Another advantage obtained by interconnecting the 40 finder switches and automatically bridging the line in the manner described is found in connection with their operation to be that if the one which is started originally skips or fails to find the line its side switch arm such as f^{34} , will automatically connect another switch to the starting circuit, causing the second switch to be actuated and this without the knowledge or the performance of any act on the part of the calling subscriber. 45

50 *The operating of the finder switches.*— Referring to Fig. 3 it will be seen that the private magnet P of each finder switch receives current from the battery Z^s and controls an armature i , connected to the wire i' leading from the side switch wiper f^{33} .

When this magnet is energized the armature i is attracted into engagement with the contact i^2 connected by the wire i^3 with one end of the coil of said magnet.

The operating circuit of the vertical magnet F^{23} is normally open at contact i^6 to which it is connected by wire i^5 this circuit is closed by the armature i^4 when the private magnet P is energized; by the attraction of the armature i^4 , which armature is connected to the rotary magnet F^{18} by wire i^7 which also connects to wire i^9 to which interrupted battery current is supplied either by a continuously operating interrupting machine, such as is sometimes employed for this purpose, or an intermittently operating relay Z^6 which latter form of interrupter I prefer to use, as it may be operated only when a call is originated and arrested when one or more of the finder switches has performed its function. This single interrupter may be used for supplying battery current to a plurality of finder switches and in its preferred form I arrange this relay in an independent starting circuit i which is adapted to be energized whenever any of the group actuated master relays are energized. Consequently this circuit leads to a plurality of forward contacts j^1, j^2, j^3 , etc., of armatures or contact springs j^{11}, j^{12}, j^{13} , etc. (Figs. 5 and 6). The starting wire j is connected to one end of the winding of relay Z^6 the other extremity of which receives current from the battery Z^t , over the armature j^{25} which is held in engagement 100 with the back contact j^{26} and the wire j^{27} . The relay Z^6 is preferably made sluggish in its action, while the armature j^{25} is retracted by a relatively heavy spring which is adjusted to such a tension as to require 105 the magnetic strength of the relay to rise to nearly its maximum point, so that the armature is somewhat slow in pulling up while in releasing its action is comparatively quick on account of the strength of 110 the spring which retracts the armature as soon as the circuit of the relay has been broken and before the magnetism has been entirely discharged from its core. In its attracted position the armature j^{25} engages 115 the contact i^8 of the wire i^9 joined to the wire i^7 and supplies an impulse of current which at different times is employed for operating the vertical and rotary magnets. In Figs. 5 and 6 the wire i^9 is shown extended to supply battery current for these 120 magnets of all the finder switches.

When a plurality of finder switches is employed the corresponding contacts on the decimal test strips or combs are connected 125 by trunks as indicated by g^5 in Fig. 5.

The rotary magnet F^{18} , one end of which is connected with the wire f^{41} , is also operated at the proper time by current impulses supplied by the interrupter Z^6 and to this 130

end, it is connected to the wire i^9 , by the wire i^7 .

The release magnet F^{34} is connected to one side of the battery Z^5 by the wire f^{52} and by the wire f^{53} to the last contact in each row or level of the bank traversed by the brush f^{17} , which are indicated by f^{54} in Fig. 3. The contacts f^{54} are extra ones and those of the banks corresponding thereto and in the same tier, which are traversed by the other brushes or wipers are unoccupied or dead. These contacts f^{54} are not involved in the usual release operations but serve to supply the impulse of current to release the switch and permit the shaft to rotate in its retrograde movement on whatever level it may have been operated and to restore it to its normal position in the event the wipers skip or fail to pick up the terminals of a calling line for any cause. The ordinary full release operation can not be conveniently described except in conjunction with the mechanism of the connector switch so that the description of the operation of this magnet which occurs when a calling party hangs up his receiver, much be deferred until the details of the connector switch have been set forth.

The operation of the finder switch will now be readily understood by considering the successive movements which occur from the moment a calling subscriber closes his telephone instrument circuit by the removal of his receiver 2 from its supporting hook and until the terminal contacts of the line are picked up by the switch wipers. The closing of the subscriber's instrument circuit at the point A^3 causes current to flow through the individual line actuated relay A^5 over the following circuit: Battery Z^3 , relay A^5 , wire a' , contact a^2 , armature a^6 , wire a^3 , substation A, wire a^{12} , armature a^4 , contact a^{13} , ground z^2 . The attraction of the armature a^5 which then occurs, closes the circuit through the group actuated master relay G over the following circuit: Battery Z^2 , relay G, wire g , contact g' , armature a^5 , wire z^4 . The last mentioned relay attracts its armatures g^4 and j^{11} , the former closing the circuit of the private magnet P of the finder switch allotted to the group of lines in which instrument circuit A appears over the following path: Battery Z^5 , wire h^2 , magnet P, wire h^{11} , contact h^{31} , spring h^{21} , contact h' , side switch arm f^{24} , starting wire p' , contact g^6 , armature g^4 , ground z^5 . The starting impulse of current was also applied at the same instant to the relay Z^6 by the armature j^{11} which closed the following circuit: ground z^5 , armature j^{11} , contact j' , wire j , relay Z^6 , wire j^{27} , contact j^{26} , armature j^{25} , battery Z^6 .

The energizing of the private magnet P attracts the armature i' in the circuit of the vertical magnet F^{23} and also closes the hold-

ing circuit of the private magnet by the attraction of the armature i which then receives an impulse of current from the battery Z^5 , the side switch arm f^{33} then being in the normal position and the switch shaft F^{10} also being in its lowermost position with the contact arm f^{28} in engagement with the contact f grounded at z^5 . The impulse of current traversing the following path: Battery Z^5 , wire h^2 , magnet P, wire i^3 , contact i^2 , armature i , wire i^7 , side switch arm f^{33} , contact f^{44} , wire f^{45} , wiper f^{28} , contact f , ground z^5 retains the private magnet energized in addition to the impulse of current received over the starting wire h^{11} . The booster line or starting circuit causes the magnet P to close the circuit of the vertical relay F^{23} and the circuit last described closes the holding circuit of the private magnet before the vertical relay takes its first step to open the off normal contacts h^{21} , h^{31} . The vertical magnet F^{23} then receives interrupted current each time the armature j^{25} is attracted over the following circuit: Battery Z^7 , armature j^{25} , contact j^8 , wires i^9 , i^7 , contact i^6 , armature i^8 , wire i^5 , vertical magnet F^{23} , wire f^{39} , contact f^{38} , side switch arm f^{22} , ground z^7 . Each energization of the vertical magnet causes the switch shaft F^{10} to move upwardly one step, advancing the wiper f^{28} successively into engagement with the group terminals on the decimal strip f^{29} which continues until said wiper engages the contact of an open branch circuit, such as g^2 , in Fig. 3. Whereupon the holding circuit of the private magnet P is opened, allowing the armatures i and i^4 to be retracted, the latter opening the circuit of the vertical magnet F^{23} , at the same instant the deenergization of the private magnet permits the side switch to escape into the second position to connect in the rotary magnet E^{18} .

The first step of the side switch moves all of its arms into the second position and the arm f^{32} cuts out the vertical magnet F^{23} and cuts in the rotary magnet F^{18} when said arm engages the contact f^{40} to close the following circuit: ground z^7 , arm f^{32} , contact f^{40} , wire f^{41} , magnet F^{18} , wires i^7 , i^9 , contact i^8 , armature j^{25} , battery Z^7 , current from the latter being intermittently supplied as the previously described circuit of the interrupting relay Z^6 is still maintained. Arranged on the rotary magnet is an armature r which is attracted by said magnet into engagement with a forward contact r' to close the circuit formed by the wires r^2 and r^3 which are joined respectively to the wires h^{11} and i' to energize the private magnet P upon the first actuation of the rotary magnet and to set the escapement mechanism in position to be immediately released as soon as the circuit of the private magnet P, which is then being held up by current received 130

over the brush f^{18} is broken for the purpose of allowing the side switch to take a second step to disconnect the circuit of the rotary magnet. Upon the first step of the side switch the arm f^{33} thereof engages the terminal f^{60} of the wire f^{61} connected to the brush f^{18} so that during the rotary movement of the switch said wiper successively engages the terminals, such as f^{16} , of the line finding test wires, such as A^{15} , all of which, with the exception of the one corresponding to the calling instrument circuit, are closed to ground or to the grounded side of the battery, so that current is retained in the private magnet P during the rotary movement of the switch until the wiper f^{18} engages the terminal of the line finding test wire of the calling line, which is open at the point a^{15} , as shown in Fig. 3, whereupon the side switch is allowed to take its second step and move into the third position. This control of the rotary movement of the finder switch automatically, will be understood more clearly by reference to Fig. 2, from which it will be seen that the set of contacts dedicated to instrument circuit A are arranged in the same position in reference to the sets of contacts dedicated to circuits B and J, as they occupy in Fig. 3, that is, they are shown in the third tier so that the switch wipers are rotated three steps before coming in contact with the set of terminals of instrument circuit A. In Fig. 2 the line finding test wires of instruments B and J are indicated by B^{15} and J^{15} terminating in the second and first contacts respectively, indicated by 161 and 162 appearing in front of the contact f^{16} in reference to the direction of rotation of the switch wiper of the test wire A^{15} . Upon the first rotary movement of the finder switch the brush f^{18} completes the following circuit: battery Z^5 , wire h^2 , magnet P , wire i^3 , contact i^2 , armature i , wire i' , side switch arm f^{33} , contact f^{60} , wire f^{61} , wiper f^{18} , contact 162, wire J^{15} , to ground. This impulse of current holds the private magnet P energized while the second impulse of current is applied to the rotary magnet F^{18} completing the second similar holding circuit over terminal 161 of wire B^{15} , again holding the magnet P energized while the third impulse of current is applied to the rotary magnet. When the wiper f^{18} picks up the contact f^{16} the private magnet P is allowed to become deenergized because the line finding test wire A^{15} is open at the point a^{15} , as before described, and the escapement mechanism being released allows the side switch arms to jump into the third position thereby discontinuing the rotary magnet of the switch and arresting it in the operated position with the wipers F' and F^2 in engagement with the line terminals A^{10} and A^{20} of the wires A' and A^2 .

The instant the side switch moves into its third position the arm f^{32} thereof applies the ground to the circuit of the wiper f^{17} to energize the cut-off relay of the calling line, which in turn deenergizes the individual line actuated relay and the group actuated relay and opens the shunt in the instrument circuit cutting the latter through to the calling subscriber's instrument and placing the circuit under his control, so that the connector switch may be operated or the finder switch released and restored to its normal position.

The complete circuit of the cut-off relay may be traced on Fig. 3, illustrating the aforescribed operations in respect to instrument circuit A: battery Z^5 , cut-off relay A^6 , wire A^{16} , terminal f^{16} , wiper f^{17} , wire f^{43} , contact f^{42} , side switch arm f^{32} , ground g^7 . The energizing of relay A^6 attracts armatures a^4 and a^6 with the consequent de-energization of the relay A^5 . The latter allows the armatures a^5 and a^{23} to be retracted, the former opening the circuit of the group actuated master relay G and the latter opening the shunt in the line circuit. The armatures g^4 and j^{11} being restored to their normal position the movement of the current interrupter Z^6 is arrested and the multiple contacts on the various decimal strips or combs joined by the wires g^2 and g^5 are connected to ground to permit any other switch which may happen to engage said strip contact to continue its vertical movement and pass beyond it.

The connector switch.—The connector switch comprises apparatus common to all the incoming lines which is rendered operative as soon as the finder switch has selected the particular line on which a call has been originated. The movement of this switch is controlled by mechanism which is actuated by impulses of current despatched in any suitable manner, but preferably by an impulse transmitter, such as that indicated by A^4 , located at the subscriber's station. This mechanism has for its primary object to control the operation of the movable contact elements or wipers C' , C^2 to permit their adjustment into engagement with the terminal contacts of any instrument circuit on said switch, and further, to render the circuit so connected (the outgoing called line) engaged or busy to prevent the called subscriber from attempting to set up a different connection through these finder and connector switches F and C at this time.

Additional devices are incorporated with the mechanism controlling the connector switch, whereby after a called party has answered in he may destroy the connection and establish another connection over a different group of switches with a third subscriber's line. These additional devices also include means for automatically despatching to a

calling subscriber, what is termed a busy signal in case the line of the party with whom he desires to communicate is otherwise in use.

5 Among those persons versed in this art it is customary to designate the two conductors of the telephone circuit (such as A', A², 4, 5 and 4^A, 5^A), as the line and mate wires and as these expressions will serve to elucidate further description, this nomenclature 10 will be adopted.

In tracing the circuit from the switch F to the switch C it will be seen that the line and mate wires 4 and 5 leading from the 15 brushes F' and F² (Fig. 3), are extended as indicated by 4, 5, 4^A and 5^A (Fig. 4) to the wipers C' and C² of the switch C and have interposed therein condensers 47 and 48. The line and mate conductors 4 and 5, 4^A 20 and 5^A form the tie between the finder and connector switches and leading from these conductors are branches 40^A and 50^A, each of which is connected respectively to one end of the coil of the line and mate relays 25 41^A and 51^A, said coils being arranged in tandem, thereby serving to balance the line. The other ends of the coils of these relays are connected to opposite sides of the battery Z, the current from which causes both 30 the line and mate relays to be energized when the brushes F' and F² of the finder switch F are in coöperative engagement with the terminals of the incoming line. Associated with the line and mate relay 35 35 tandem coils 41^A and 51^A is the holding over or slow operating relay L, one end of the coil of which is connected by the wire l to one of the poles of battery Z and to one end of the coil 41^A; the other extremity of the 40 winding of relay L is extended by the line l' to the forward contact l² of a normally open armature l³ of the line and mate relay. The relay L is preferably made slow or sluggish in its action by surrounding its core with a 45 copper jacket or otherwise constructing it, so that when it has once been energized by the attraction of the armature l³, which occurs when the calling line is cut through to the connector switch, it will retain the magnetism in its core during the vibration of the 50 armature l³, while the latter is vibrated by current impulses in the line and mate relay which may be transmitted thereto successively at regular intervals of time, for purposes as will presently appear.

The connector switch is similar to the finder switch previously described in that it is operated vertically and rotated, by separate magnets designed for this purpose 60 which are automatically brought into circuit by a side switch controlled by a private magnet, said switch mechanism also comprising a release magnet for restoring its parts to normal, together with means for 65 signaling a called party and devices for re-

turning to the calling party the tone or busy signal in the event the line of the party with whom a subscriber is endeavoring to establish a connection, is otherwise in use.

In Fig. 4 a single connector switch and the operating mechanism therefor is illustrated diagrammatically, the switch shaft being indicated by C¹⁰ on which is mounted the wipers C', C² and c. The side switch of the connector comprises four connected arms c', c², c³, c⁴, the first two of which are interposed in the tie wires 4^A and 5^A leading from the finder switch and are adapted to coöperate with the terminals c⁷, c⁸ of the wires c', c³, leading to the wipers C' and C². Said switch arm c³ in its normal position engages the terminal c⁹ of the wire c¹⁰ of the vertical magnet C²³ and in the second position it coöperates with the terminal c¹¹ of the wire c¹² forming part of the circuit of the rotary magnet C¹⁸. The side switch in the second position causes its arm c⁴ to engage the contact c¹³ and in its third position said arm rests upon the contact c¹⁴ grounded as indicated at z⁹. The side switch arm c³ is connected by the wire c¹⁵ to a back contact c¹⁶ of the armature l⁸ which is grounded as indicated at z', and the remaining portion of the circuit of the vertical relay C²³ is formed by the wire c¹⁷ connected to the armature c¹⁸ arranged on the slow relay L and by the latter attracted into engagement with the forward contact c¹⁹ forming the terminal of the battery Z, and as the latter serves to supply current for operating the rotary magnet C¹⁸, one end of the latter is connected to the wire c¹⁷ by a tap c²⁰.

The calling instrument circuit A may be traced over the following path: instrument A, line wire A', contact A¹⁰, wiper F', wire f³⁷, contact f³⁵, side switch arm f³⁰, wire 4, wire 40^A, one coil of line relay 41^A, one coil of relay 51^A, battery Z, other coil of relay 51^A, the other coil of relay 41^A, line 50^A, mate 5, side switch arm f³¹; contact f³⁶, wire f³⁸, wiper F², contact A²⁰, mate wire A². When the circuit just described is connected through, it is energized from the battery Z, causing the armature, l⁸, to be attracted to close the circuit of the relay L, which is retained energized during the successive vibrations of the armature l³. The last mentioned relay attracts and by reason of its sluggish operation holds attracted the armature c¹⁸. Now, suppose the instrument circuit with which it is desired to effect a connection, is that represented by B in Fig. 4, the terminals B¹¹ and B²¹ of which are arranged in the second levels and the third tier of contacts in the terminal banks. The calling subscriber then despatches two impulses of current in regular succession by the operation of his impulse transmitter, such as A⁴. Each time the circuit is broken the armature l³ of the line and mate relay

- coils is allowed to fall back into engagement with the contact c^{16} to close the following circuit: battery Z, contacts c^{19} , armature c^{18} , wire c^{17} , vertical magnet C^{23} , wire c^{10} , contact c^9 , side switch arm c^8 , wire c^{15} , contact c^{16} , armature l^3 , ground z' . At each impulse through relay 51^A the armature, l^3 , responds and energizes the vertical magnet C^{23} , a corresponding number of times, stepping up 5 the shaft C^{10} , as many steps as there are impulses, in this case two, or to the second level. As soon as the switch shaft C^{10} , moves off-normal it closes the off-normal contact, c^{21} , by switch spring c^{22} . This 10 closes a circuit through a private magnet C^{24} , as follows: from ground at z' , armature l^3 , contact c^{16} , wire c^{15} , wire c^{23} , private magnet C^{24} , wire c^{24} , wire c^{25} , contact c^{21} , switch spring c^{22} , wire c^{26} , through the release magnet 15 net C^{25} , to battery Z' , and ground at z' . The private magnet, C^{24} is thus energized. It will be noticed that the above described circuit also includes the release magnet, C^{25} , but the resistance of the private magnet is 20 such that, while it will be properly energized through the release magnet, C^{25} , to perform its functions, the said release magnet will not receive sufficient current to become operatively energized. 25 The private magnet, C^{24} , is a slow magnet or relay and holds over while the armature, l^3 , vibrates in response to impulses through the line relay, 51^A . When the impulses cease the armature, l^3 , remains held up and 30 breaks the circuit of the private magnet, C^{24} , at the contact, c^{16} , thus deenergizing the private magnet and allows the side switch arms, c^1 , c^2 , c^3 and c^4 , to move to second position. The switch arm, c^8 , moving 35 to second position contacts with the terminal, c^{11} , of wire, c^{12} , which leads to the rotary magnet, c^{18} . The rotary magnet is now ready to receive impulses sent over the line and through the line relay, 51^A , through the 40 following circuit: from battery Z, wire l , contact c^{19} , armature c^{18} , wire c^{17} , wire c^{20} , rotary magnet C^{18} , wire c^{12} , terminal c^{11} , switch arm c^8 , wire c^{15} , contact c^{16} , armature l^3 , and ground at z' . The rotary magnet 45 responds to the vibrations of the armature, l^3 , as often as the same is vibrated by the impulses passing through the line relay, 51^A , which, in this case, would be three. This causes the wipers, C^1 , C^2 and c , to move 50 over as many contacts in the respective banks as there are impulses. As soon as the armature, l^3 , drops back by the first interruption of the current passing through the magnet 51^A , the private magnet, C^{24} , is energized over the same circuit, as before described, and, being a slow magnet holds up 55 during the interruption and until the switch shaft has been rotated a number of steps corresponding to the impulses, after which 60 the private magnet is deenergized by the 65

breaking of its circuit at contact c^{16} by the drawing up of the armature, l^3 , toward the line relay 51^A ; this allows the side switch arms, c^1 , c^2 , c^3 and c^4 , to pass to the third position, which extends the line 4^A and 5^A 70 through the side switch arms, c^1 , c^2 , the wipers, C^1 and C^2 , terminals, B^{11} , B^{21} , to the lines B^1 , B^2 , of subscriber's station B. The lines are now connected ready to receive 75 signaling currents which are supplied as follows: The closing of the push button, A^7 , puts ground on one side of the line and opens the other side of the line. Grounding this side of the line allows the relay 51^A to hold up through one of its windings, but 80 grounding one side of the line and breaking the other side causes the differential relay 41^A to be energized through one of its windings and thus includes the generator, h , in a circuit through contacts h^1 , armature h^2 , 85 contact h^3 , and armature h^4 , thus putting generator current on the lines 4^A , 5^A , which are connected to armatures K^3 and K^4 .

When the connector switch, C, rotates to bring the wipers, C^1 and C^2 , on the contacts, B^{11} , B^{21} , thus extending the talking circuit or subscriber's line to station B, wiper c on said switch, C, drops onto contact c^{27} , and thus closes a circuit through the cut-off relay B^6 , as follows: from ground at z^9 , 90 through terminal c^{14} , switch arm c^4 , which has moved to third position, wire c^{28} , contact c^{29} , armature c^{30} , wire c^{31} , to wiper c , contact c^{27} , wire c^{58} , cut-off relay B^6 , battery Z^{11} , and ground. This puts ground on the 100 terminal c^{27} .

In case the subscriber B is busy, then the relay, B^6 , would have been operated by some other switch putting ground onto the contact c^{27} , which would operate the busy 105 relay C^{27} . This would occur immediately upon the wiper, c , contacting with terminal c^{27} , which would be prior to the time that the side switch arms move to the third position after the private magnet had dropped 110 back. The circuit through which this busy relay, C^{27} , is energized, being as follows: from ground at c^{27} , wiper c , wire c^{31} , armature c^{30} , contact c^{29} , wire c^{28} , switch arm c^4 , contact c^{13} , wire c^{32} , through one winding of 115 the differential relay C^{27} , wire c^{33} , armature c^{18} , contact c^{19} , wire l , battery Z, to ground. The energizing of the differential relay, C^{27} , would release the connector switch, C, as follows: from ground at z^{11} , armature 120 c^{34} , contact c^{35} , wire c^{36} , wire c^{25} , off-normal contact c^{21} , switch spring c^{22} , wire c^{28} , release magnet C^{25} , battery Z' , to ground at z^9 . This releases the connector switch and permits it to return. The relay, C^{27} , in becoming energized, locks itself in energized 125 position, as follows: ground z^{12} , line c^{37} , primary side of tone coil, wire c^{38} , contact c^{39} , armature c^{40} , line c^{41} , wire c^{32} , wire c^{33} , armature c^{18} , contact c^{10} , line l , battery Z, to 130

ground. This sends a busy signal back from induced currents on the primary of the tone coil through wire c^{38} , armature c^{40} , wire c^{41} , wire c^{42} , through the condenser 48 onto the line 5, thus disturbing the balance of the line and giving a busy signal to the calling subscriber.

When subscriber A is talking to subscriber B the source of battery supply of subscriber A would be from battery Z, through relays 51^A and 41^A, but the condensers 47 and 48 would prevent the flow of this battery through coils 51^A and 41^A to subscriber B and battery is supplied to subscriber B through coil C²⁷, as follows: ground, battery Z, wire l, contacts c^{19} , armature c^{18} , wire c^{38} , one coil C²⁷, wire c^{42} , wire c^{42} , contact k^5 , armature k^2 , and to one side of the line 5^A. From ground at z^{12} , through coil C²⁷, wire c^{43} , contact k^6 , armature k^4 , to other side of line 4^A. It will be understood, however, that relay C²⁷ is a differential relay and will not be energized by the flow of battery to subscriber B.

It should be noted that if subscriber A gets the busy signal he would have to hang up, which would deenergize the line relay, 51^A, which in turn, breaks the circuit of the slow relay, L, which, in turn, breaks the circuit of the busy relay, C²⁷.

When the calling subscriber hangs up he puts ground from z' , onto the contact c^{16} , wire c^{46} , armature c^{47} , wire c^{36} , wire c^{25} , off-normal contact c^{21} , switch spring c^{22} , wire c^{26} , release magnet C²⁵, battery Z', to ground at z^9 . This releases the connector switch and closes the circuit to the finder switch at the armature c^{48} , as follows: from ground at z' , armature k^3 , contact c^{16} , wire c^{15} , wire c^{49} , armature c^{48} , contact c^{50} , wire c^{45} , through release magnet F³⁶, to battery, which releases the finder switch and permits the parts to return to their normal position.

Having thus described my invention, I claim:

1. A series of subscribers' circuits arranged in groups, a series of switches less in number than the number of subscribers' circuits, said switches each having different levels corresponding in number to the number of groups, a certain one of said series of switches being normally allotted to each group, means for preselecting an idle one of said series of switches if the normally allotted switch is busy, a master relay for each group and means for energizing said master relay upon the initiation of a call, said relay operating to cause said preselected switch to select the group of lines represented by said relay.

2. In an automatic telephone system, a two-movement switch comprising a brush supporting shaft capable of longitudinal and rotary movement, a vertical magnet for moving said shaft longitudinally, a rotary

magnet for moving said shaft rotatively, bank contacts arranged in different levels corresponding to the number of vertical steps of said switch, and a commutator having contacts also corresponding to the number of levels of said switch, and a wiper adapted to successively engage said commutator, and a connection from said wiper to supply current to the vertical magnet, and means for connecting said current supply to said vertical magnet whenever the switch is moved off-normal and so long as a circuit is established through said commutator.

3. A series of subscribers' stations arranged in groups, and a series of switches having different bank contacts arranged in different levels, one level for each group, a master relay for each group of subscribers, a series of switches corresponding to the number of groups of subscribers, multiple connections of the subscribers' circuits to each of the switches, means including branch operating circuits controlled by said master relays for moving said switches vertically when started by the operation of the master relay, and for continuing said movement until the level corresponding to the operated relay is reached.

4. In an automatic telephone exchange system, a finder switch having a vertical and rotary movement, a vertical magnet, a rotary magnet, a side switch, a private magnet for operating said side switch, a commutator having a series of contacts equal to the number of vertical steps in said switch, and a wiper on the switch shaft adapted to successively engage said contacts as said switch is moved vertically, and a connection from said wiper through said side switch to the private magnet whereby said private magnet is held energized and controls the vertical magnet to cause the switch to step up so long as current is supplied through said commutator to said private magnet.

5. A series of subscribers' circuits arranged in groups, a series of switches less in number than and common to said subscribers' circuits, each group of circuits having a certain one of said switches normally allotted thereto, a starting circuit for each of said switches, and means operated when a switch is taken for use for extending said starting circuit to an idle switch of said series.

6. A series of subscribers' circuits arranged in groups, a series of switches less in number than the number of subscribers' circuits, common thereto, each group having a certain switch of said series normally allotted thereto, said switches each having different levels corresponding in number to the number of said groups, a master relay for each group, starting wires, one for each master relay, means for maintaining said starting wires extended to an idle switch,

means for actuating a master relay upon initiation of a call, and contacts operated by said relay for completing a starting circuit, whereby an idle switch will be caused to 5 hunt for the level corresponding to the calling line.

7. In a telephone system, groups of incoming lines, a plurality of switches common to said lines, each group having a certain switch normally allotted thereto, means actuated when a switch normally allotted to a group of lines is taken for use for selecting an idle switch and definitely associating it with said group of lines, and 15 means whereby the preselected switch will be operated to select the terminals of a line in said group upon which a call is initiated.

8. In an automatic switch having a vertical and rotary movement, a vertical magnet and a rotary magnet and a private magnet for supplying operating current to said vertical and rotary magnets, a starter wire leading to said private magnet having a make-and-break contact adapted to 20 be opened on the first movement of the switch, a wiper on said switch, contacts equal in number to the vertical steps of said switch adapted to be engaged by said wiper, means for supplying current through each 25 of said contacts, and a connection from said wiper to said private magnet to cause current to be supplied to said private magnet through said contacts and thus operate the vertical magnet until said current supply 30 is broken at one of said wiper contacts, and a side switch adapted to be operated by said private magnet to change the operating current from said vertical magnet to said rotary magnet when said switch has reached 35 the limit of its upward movement as determined by the current supplied through said wiper contacts.

9. The combination with a vertical and rotary switch, a series of subscribers' telephone lines, each having line relays and each connected to said switch in groups corresponding to the different levels to which said switch moves, a master relay for each group, a commutator having sections corresponding to the number of different levels, each of said sections being normally grounded through a circuit breaker operated by said master relay, a wiper on said switch, an electrically-operated current supply controlling device having a connection to said wipers, and a circuit closing device also operated by said master relay to close the circuit through said electrically-operated current controlling device when said master relay is operated, a circuit breaker in said last-mentioned circuit adapted to be opened at the first movement of said switch whereby the closing of any of said subscribers' lines will energize the master relay pertaining to that 55 group and thus start said switch and cause

the same to continue its vertical movement until it has moved to the level corresponding to said group.

10. In an automatic telephone exchange, a series of subscribers' lines arranged in groups, and a master relay for each group, an automatic switch having a vertical and rotary movement, each of said lines being connected to terminals in said switch with the lines of each group on a different level 70 in said switch, means in each of said lines for operating the master relay of the group, a commutator having a series of sections corresponding to the number of levels in said switch, each of which is connected to a 75 circuit closing device adapted to be operated by said master relay, a wiper on said switch adapted to successively engage the contacts on said commutator, an electrically-operated device connected to said wiper for 80 controlling the current supplied to the operating mechanism for said switch, a starting wire common to all the groups also connected to said electrically-operated controlling means, and a circuit breaker in said 85 starting wire adapted to be broken on the first movement of said switch, and a source of current supply for said starting wire and also to the circuits including the commutator sections whereby the closing of the line 90 in any group will cause the switch to automatically start and move to the level occupied by that line.

11. The combination with a series of subscribers' lines arranged in groups, a master 100 relay for each group, a vertical and rotary movable switch having a series of groups of contacts arranged in different levels corresponding to the number of groups of subscribers' lines, each of said subscribers' lines 105 being connected to one of the terminals in one of said groups, a master relay one for each group, means for operating said master relay upon the closing of the subscriber's line in said group, a commutator having a 110 series of contacts adapted to be supplied with current when said master relay is not operated, a wiper on said switch adapted to successively engage the contacts on said commutator when the switch is moved vertically, operating means for moving said switch vertically and rotatively, and a private magnet for controlling the current supplied to said operating means, and a connection from said wiper to said private magnet 115 whereby current is supplied to said private magnet so long as the wiper engages the contact to which current is supplied, a starter wire also connected to said private magnet, and means for supplying current 120 for said starter wire adapted to be operated upon the closing of any subscriber's line connected to said switch, a circuit breaker in said starter wire adapted to break said circuit upon the first movement of the switch, 125 130

and a side switch operated by said private magnet when the switch has been moved until it rests upon a commutator section not supplied with current, said side switch being adapted to change the current supplied from said vertical magnet to said rotary magnet, and means connected with each subscriber's line in normal position to furnish current to said private magnet and to break said current supply when said subscriber's line has been closed whereby the switch is automatically started and moved to the level corresponding to the group in which said subscriber's line is located and is rotated until the subscriber's line is found.

12. A series of telephone wires arranged in groups and a series of vertically and rotatively movable switches each having a number of levels corresponding to the number of groups, a starting wire running from each group to one or more of said switches, means connected with said switches when a subscriber's line in any one group is closed to cause the switch to automatically operate both vertically and rotatively to find said line, and an auxiliary switch operated by the main switch adapted to extend said starting line to one or more of the other switches of the series when said switch has been operated.

13. A series of subscribers' lines arranged in groups and a series of vertically and rotatively movable switches each having a series of contacts arranged in different levels and corresponding to the number of groups, each level having a number of contacts corresponding to the number of lines in the group, said lines being connected in multiple to different contacts in the different switches, a master relay connected to each group and adapted to be operated whenever a subscriber's line in said group is closed, and means controlled by said master relay for starting one of said switches and causing it to operate vertically and rotatively until it finds the line closed, and an auxiliary switch connected with said operated switch to cause said master relay to be connected with one or more of the other switches, as specified.

14. In an automatic telephone exchange, a connector switch, two line relays connected in tandem, one of said relays adapted to operate the connector switch and the other a differential relay adapted to close a ringing circuit, a differential relay adapted to close a busy circuit, said differential relays being adapted to supply battery to the calling and called subscribers, respectively.

15. In a finder switch having a vertical and rotary movement, means for imparting the respective movements to said switch, an electrically-operated device for controlling respectively and successively the vertical and rotary movements of said switch, a com-

mutator connected to said switch, and a wiper in electrical connection with said electrically-operated controlling device, a source of electrical supply normally closed circuits from said source to the different sections of said commutator, means for starting said switch to cause the wiper to engage with successive commutator sections so as to supply current to said vertically-operated controlling device from each of said commutator sections having current supplied thereto.

16. In connection with a series of subscribers' circuits arranged in groups, a finder switch having a vertical and a rotary movement, means for producing this vertical and rotary movement, an electrically-operated controlling device adapted when successively operated to supply energy to the vertical and the rotary devices of said switches, a commutator having different contacts, an electrically-operated device for each group of subscribers normally connected to one of said contacts, and means connected with said subscriber's operating device for establishing a circuit through said switch-controlling device on the closing of any subscriber's line and for breaking the circuit corresponding to said group to said commutator whereby upon the closing of any line the switch-controlling device is caused to operate and to keep the switch in operation so long as current is supplied to the switch-controlling device through said commutator.

17. In combination with a series of subscribers' circuits arranged in groups, a plurality of switches, each of said groups being connected in multiple to terminals in said plurality of switches, a line relay for each subscriber's circuit, and a master relay for each group, a starter wire normally leading to a switch assigned to that group and connected to an electrically-operated controlling device for said switch, means for closing the circuit through the said starter wire and said electrically-operating controlling device when said master relay is operated, and an auxiliary switch for disconnecting said starter wire circuit when the switch is started and for extending said wire to another switch to which said group is connected in multiple when said first switch has completed its operation.

18. In a telephone system, subscribers' lines arranged in groups, a switch for connecting same, each group being connected in multiple to a plurality of switches, line and cut-off relays for each subscriber's circuit, a master relay for each group adapted to be controlled by said line relay, a shunt in each subscriber's circuit also adapted to be controlled by said line relay, said line relay adapted to be disconnected by said cut-off relay, a starting wire from the master relay

1 to a switch assigned to said group, an electrical controlling device for said switch normally included in said starting wire circuit, means for furnishing current to said starting wire circuit upon the movement of said master relay, and an auxiliary switch connected with said finder switch adapted to disconnect said starter wire from said switch and to extend said starter wire to another 5 switch to which said group is normally connected when said first switch has been operated.

19. In an automatic telephone system, a two-movement finder switch subscribers' circuits arranged in groups, a master relay for each group, each group of subscribers being connected to terminals at a different level in said two movement finder switch, an electrical controlling device for each switch 15 adapted to be set in operation by the movement of said master relay, and means including a commutator for continuing the movement of said switch after said master relay has operated until said switch finds the 20 terminals of the subscriber's circuit operated, a connector switch having wipers adapted by the operation of said finder switch to be brought into connection with the subscribers' lines which cause the operation of said finder switch, electrically operated means for operating said connector switch, and relays including a slow relay for controlling the movement of said switch-operating devices by impulses upon the subscribers' line connected thereto whereby 25 said connector switch may be operated to find the terminals of any line to be connected.

20. A series of subscribers' circuits arranged in groups, a series of switches less in number than the number of subscribers' circuits, said switches having different levels corresponding in number to the number of groups, a master relay for each group, a normally open starting circuit and a normally closed operating circuit controlled by said master relay, and means connected with the switch for starting the vertical movements thereof when said starting circuit is closed and for continuing the movement thereof by current supplied over the operating circuit branches, substantially as specified.

21. A series of subscribers' circuits arranged in groups and a series of switches less in number than the number of subscribers' circuits, said switches having different levels corresponding in number to the number of groups, a master relay for each group operated by the closing of the line in any group and normally open starting circuit and a normally closed operating circuit controlled by the master relay, means connected with said switch for producing

an initial movement of said switch when 65 the starting circuit is closed, and means on said switch including a commutator for successively supplying current over said operating circuits to continue vertical movement of said switches. 70

22. A series of subscribers' circuits arranged in groups, and a series of switches less in number than the number of subscribers' circuits, said switches having different levels corresponding in number to 75 the number of groups, a master relay for each group operated by the closing of the line in any group and normally open starting circuit and a normally closed operating circuit controlled by the master relay, means connected with said switch for producing an initial movement of said switch when the starting circuit is closed, and means on said switch including a commutator for successively supplying current over said operating circuits to continue vertical movement to said switches, and means connected with each switch for extending the starter wire to another switch when said switch is operated. 80

23. In combination with a series of subscribers' circuits arranged in groups, a vertically and rotatively movable switch to which said lines are connected, the terminals of said lines being arranged in said switch 90 in groups corresponding to the line groups, a line relay for each circuit and a master relay for each group, a starter wire controlled by said master relays normally leading to a switch assigned to the group and 95 connected to an electrically operating controlling device for the switch, means for closing a circuit through the starter wire when the master relay is operated, and an auxiliary device for disconnecting said 100 starter wire circuit when the switch is started, and means for extending said starter wire to another switch when said first switch has completed its operation. 105

24. In an automatic telephone system, a connector switch, a line circuit comprising two talking conductors, a line relay included in a series circuit with said two conductors and responsive to interruptions in the line circuit to control the operation of the connector switch, a differential line relay not responsive to interruptions in the line circuit, and means at the calling station to ground one side of the line circuit to operate said differential relay and project ring- 110 current over the called line. 115

25. In an automatic telephone system, a connector switch, a line circuit comprising two talking conductors, a line relay included in a series circuit with said two conductors 120 and responsive to interruptions in the line circuit to control the operation of said connector switch, a test relay, means operable 125

when the switch is connected to a busy line to operate said test relay, a release magnet, a busy test circuit, and means to simultaneously operate the release magnet and apply the busy test when the test relay is operated.

26. In an automatic telephone system, a connector switch, a line relay responsive to line interruptions which control the operation of said switch, a test relay operable when said switch is connected to a busy line, a release magnet, a busy test circuit, means

to simultaneously operate the release magnet and apply the busy test when the test relay is operated, and a battery supply circuit for the called subscriber including said test relay.

In testimony whereof, I have hereunto set my hand this 16th day of April, 1909.

CHARLES L. GOODRUM.
